UNITED STATES PATENT OFFICE.

FRANK PARDEE, OF HAZLETON, PENNSYLVANIA.

SEPARATOR.

No. 895,889.

Specification of Letters Patent.

Patented Aug. 11, 1908.

Application filed October 10, 1907. Serial No. 396,769.

To all whom it may concern:

Be it known that I, FRANK PARDEE, a citizen of the United States, and a resident of Hazleton, in the county of Luzerne and State 5 of Pennsylvania, have invented a new and useful Improvement in Separators, of which the following is a full, clear, and exact description.

My invention relates to machines for separating substances differing in specific gravity or frictional resistance, wherein the utilization of frictional resistance is employed in connection with gravity, particularly in the separation of coal from slate.

15 A purpose of the invention is to provide a separator so constructed and arranged that different kinds of substances submitted to its action will be automatically divided or assorted.

20 A further purpose of the invention is to provide an especially designed member or a series of members adapted to retard the movement of the slate relatively to the coal so that the two said elements will be projected different distances in effecting the separation, and in the above connection to provide a surface over which the material is passed having retarding members rising therefrom and arranged in a forward direction, which members offer in effect an increased resistance from a rearward to a forward point on said surface or surfaces.

25 The invention consists in the novel construction and combination of the several parts as will be hereinafter fully set forth and pointed out in the claims.

30 Reference is to be had to the accompanying drawings forming a part of this specification in which similar characters of reference indicate corresponding parts in all the figures.

35 Figure 1 is a perspective view of a series of separating mediums arranged in consecutive and coöperating order to receive material 40 from a delivery member; Fig. 2 is a perspective view of the delivery member and a single separator in co-action therewith, the retarding members of the separator being diagonally formed as in Fig. 1; Fig. 3 is a perspective view of one of the separators or separating plates, being drawn upon a larger scale and illustrating the retarding members as extending parallel with the sides of said plate; and Fig. 4 is a perspective view of a 45 portion of a spiral separator, illustrating the

application of the improved separating elements thereto.

The device illustrated is more especially intended for the separation of coal from slate and from bone, or pieces of coal containing a kind of slate, usually in thin layers, and the invention will be described in that connection, although it is applicable to separators for other substances.

50 When anthracite coal is taken from the mines it is mixed with more or less rocky substances, usually designated as slate, which owing to its comparatively flat shape and the fact that it contains silicate or other gritty matter, offers a resistance when moving over a surface. I provide members serving as a selective surface to engage the slate and retard it to a greater degree than the less flat portions constituting the general mass of the coal. This resistance is such during the passage of mixed substances along the floor of a chute or a dump as to cause the slate or bone to move slower than the pure coal, apart from the difference in velocity due to the difference in specific gravity, the coal gliding with more rapidity and meeting with less resistance from the surface over which the several substances are made to travel, passing straight on and over the dump, while the retarded slate or bone falls into the gap or opening provided to receive it, located between the receptacle for the coal and the delivery apron for the bone and slate.

55 The difference in the nature and action of the substances render gravity force available for the purpose of separation, but that force is not wholly to be relied upon, as the substances must necessarily adjust themselves to their relative positions, which requires some to cross the course of others and occasions more or less knocking of the pieces against one another, so also the slate or rock, as well as bone, receives an impact from the surface behind it, which knocking imparts to the pieces of slate or bone greater impetus than they would have from the mere force of gravity, and unless prevented from so doing, such pieces are liable to pass over the said slit or gap and become mixed with the pure coal, but the peculiar frictional resistance which operates against the speed of the slate or bone when moving over another solid surface may be taken advantage of by mechanical means for overcoming the extraordinary impetus which they may receive, and which

will tend to change their course so that such pieces will proceed to one side of the chute and be retarded, and from said side of the chute fall free from the balance of the material.

For the purpose of attaining the object already stated, it is important that the physical properties of the different substances be separated to be utilized and the conditions that would otherwise be a hindrance should be measurably overcome, and to this end the invention consists primarily of a machine for separating ore, coal, etc., by gravitation and frictional resistance, or by a combination of both with specific gravity, composing a suitably supported separating floor on or along which the substances pass, an inlet and an outlet therefrom, the said floor being provided with an incline, the plane of which may be tilted or horizontal, and which pitches toward the outlet or apron in front of the slit or gap.

A represents a bed made of any suitable material and which is given more or less of a downward inclination and rests upon suitable supports A'. At the upper portion of the bed A, a chute 10, or other device for delivering material, is located, also having a downward inclination, and the said chute or delivering member 10 conducts the material upon a separating floor B, which floor is shown in Fig. 1 as resting on the bed A. This separating floor B may consist of one section or a series of sections C, a single section being shown in Fig. 2, and a series in Fig. 1. When the sections are in series they overlap and the bed A extends beyond the lower end of the said separating floor B to form a delivery apron 11, which is separated by a gap or slit D' from a landing floor D, as is shown in Fig. 1.

The coal passing down the separating floor moves much more rapidly than the slate or bone, and consequently makes a greater jump when it leaves the delivery apron 11 and falls upon the landing floor D, or the equivalent thereof, adapted to receive it, while the slate and bone traveling less rapidly and leaving the delivery table 11 with less force, drops into the gap or opening D', whereby a nearly perfect separation of material is obtained.

The sections C of the separating floor B are in the form of plates of any suitable size and of any desired thickness. These plates may be flat, concaved, or convexed, or partly concaved and partly convexed. Each plate is provided with a series of slits 12 that are by preference in parallelism, as is shown, and the material at one side of each slit is bent upward to form a series of retarding flanges 13 or members 13 that increase in depth as they approach the delivery end of a plate. The slits 12 extend from a point adjacent to the receiving edge portion of a plate and out through the delivery edge portion thereof so that the retarding flanges or members 13

rise practically from nothing at the rear of a plate and increase gradually in depth or width as they approach the opposing edge. These flanges therefore have located between them smooth runways 14, and while these flanges 13 may be straight, they are preferably given the inclination shown in direction of one or the other side of a plate. The flanges or retarding members 13 offer in effect increased resistance to or retard the objects engaging with them from a rearward to a more forward point upon the separating floor. These slits and accompanying flanges may be straight or parallel with the side edges of a plate, as is shown in Fig. 3, but preferably they are diagonally located, or are at an angle to the sides of the plate, and when occupying this position they tend to draw the slate or gritty material to one side, allowing the coal to pass ahead without being apparently turned aside from a straight forward path. If it is desired, the chute or delivery section of the machine may have a hinged connection 15 with the uppermost plate, or the separating plate that is adjacent to it, and I desire it to be understood that I do not limit myself to any special number of separating plates in the construction of a separating floor, nor do I limit myself to any particular means for supporting such plates or floor.

In Fig. 4 I have illustrated the adaptation of the improvement to what is known as a "spiral separator", a portion of which is shown in said figure, and the said spiral separator is made up of a series of overlapping bed plates A², and each of the said bed plates A² at a corresponding edge portion is provided upon its upper face with a separating plate C'. These separating plates C' differ from those shown in the other views inasmuch as their inner edges are inclined, the plates being narrowest at their outer edges, but these plates are also provided with parallel slits 12^a corresponding to the slits 12 described, and with adjacent retarding flanges 13^a, corresponding to the flanges 13 hereinbefore referred to and the action of the said flanges 13^a in the form of plate C' is the same as that in the form of plate C. 115

In the construction of the plates C', they are preferably strengthened at their outer or delivery edges where the slits 12 extend through, by locating a brace plate 16 at the bottom of a separating plate adjacent to its delivery edge, crossing the said slits, which brace plate 16 is rigidly secured to the plate in any suitable or approved manner.

I desire it to be understood that the flanges 13 may be at right angles to the runways 14, or at any other suitable angle; and that said flanges 13, in connection with the runways 14, afford a side frictional resistance, as well as a bottom frictional resistance to the material being separated upon the machine. For 130

instance, in the separation of coal and slate, the slate has double bottom and side friction, producing a maximum retarding resistance, while a piece of coal with a film of slate on the bottom would have a slaty resistance on the bottom, but the glossy side friction would be so slight as to cause this character of coal to move with greater rapidity than slate.

Having thus described my invention, I claim as new and desire to secure by Letters Patent,—

1. In a separator, separating plates having slits produced therein, the material being bent up at one wall of the slits to produce 15 retarding flanges.

2. A separating plate provided with slits, the material at one wall of the slits being bent up to produce retarding flanges that gradually deepen in direction of the delivery 20 end of the plate, said flanges having an inclination relatively to the general surface of the plate.

3. In a separator, a floor having parallel slits produced therein and the material of the 25 floor bent upward at one wall of said slits, the upwardly bent portions increasing in width in direction of the discharge end of the floor, forming a series of retarding flanges, which flanges have an inclination in the same direction 30 with respect to the general surface of the floor.

4. In a separator, a floor having parallel diagonal slits therein and the material of the floor bent upward at a wall of the said slits, 35 the upwardly bent material increasing in width in direction of the discharge end of the floor, said upwardly bent material constituting retarding flanges, which flanges have a

lateral inclination in the same direction relatively to the general surface of the floor. 40

5. In a separator, a separating floor consisting of a series of plates arranged to deliver one to the other, each plate being provided with a series of slits, and having the material at one wall of the slits bent upward 45 to form a series of retarding flanges that increase in depth as they approach the delivery end of the plates, said flanges having a lateral inclination relatively to the upper or receiving surfaces of said plates. 50

6. A machine for separating ore, coal, and the like, by gravitation and frictional resistance, comprising a suitably supported inclined plane provided with diagonal slits extending from its receiving in direction of its 55 discharge end, the material of said plane at one wall of said slits being bent upward, forming retarding members that offer in effect increased resistance from a rearward to a forward point on said plane, said retarding 60 members being given a lateral inclination in the said direction, the space between the retarding members forming continuous paths for the passage of material, an apron constituting a continuation of said paths, a receptacle for pure material, and a gap for the 65 reception of waste material intervening the apron and said receptacle.

In testimony whereof I have signed my name to this specification in the presence of 70 two subscribing witnesses.
